SHUTTLE MOTION FOR LOOMS

Journey F. Timberlake, Charlottesville, Va., assignor of twelve and one-fourth per cent to De Leon A. Prosser, Petersburg, Va., and twelve and one-fourth per cent to John H. Ryalls, twelve and one-fourth per cent to L. G. Wolff, and twelve and one-fourth per cent to R. Winston Dabney, all of Richmond, Va.

Application October 4, 1933, Serial No. 692,172

4 Claims. (Cl. 139—133)

The present invention relates to new and useful improvements in shuttle motions for looms, and has for its primary object to provide, in a manner as hereinafter set forth, a shuttle motion embodying a novel construction, combination and arrangement of parts through the medium of which the shuttle will be positively driven and under constant control during its entire travel through the shed.

Other objects of the invention are to provide a shuttle motion for looms which will be comparatively simple in construction, strong, durable, highly efficient and reliable in operation and which may be manufactured at low cost.

All of the foregoing and still further objects and advantages of the invention will become apparent from a study of the following specification, taken in connection with the accompanying drawings wherein like characters of reference designate corresponding parts throughout the several views, and wherein:—

Figure 1 is a view in front elevation of a shuttle motion in accordance with the present invention.

Figure 2 is a view in vertical longitudinal section through a portion of the shuttle motion, taken substantially on the line 2—2 of Figure 3.

Figure 3 is a view in vertical transverse section, taken substantially on the line 3—3 of Figure 1.

Figure 4 is a view in vertical transverse section, taken substantially on the line 4—4 of Figure 1.

Figure 5 is a detail view in horizontal section through the shuttle, taken substantially on the line 5—5 of Figure 1.

Figure 6 is a fragmentary view of an intermediate portion of the lay, said view being partially in top plan and partially in horizontal section on the line 6—6 in Figure 1 of the drawings.

Figure 7 is a horizontal sectional view, taken substantially on the line 7—7 of Figure 1.

Figure 8 is a detail view in perspective of the substantially channel-shaped face plate constituting a part of the cam.

Figure 9 is a detail view in perspective of one of the vertically reciprocating shuttle actuating pins.

Figure 10 is a detail view in perspective of one of the pin guides.

Figure 11 is a detail view in perspective of one of the pin weights.

Referring now to the drawings in detail, it will be seen that the embodiment of the invention which has been illustrated comprises a lay which is designated generally by the reference numeral

1, said lay including a pair of lay swords 2 which may be mounted for swinging movement in the usual manner. Extending between the lay swords 2 are upper and lower rails 3 and 4, respectively, between which a shuttle which is designated generally by the reference numeral 5 is mounted for travel.

As illustrated to advantage in Figures 3 and 4 of the drawings, the lower rail 4 is of hollow or substantially tubular form to receive lubricating oil substantially to the level indicated by the broken line 6. Mounted vertically in the lower rail 4 is a series of guides 7 having slidably mounted therein shuttle actuating pins 8, said guides 7 having ports 9 therein for the passage of the lubricating oil to said pins 8. The guides 7 project above the rail 4 for engagement with heads 10 on the upper ends of the pins 8, thus supporting said heads in elevated position relative to the rail 4. Polygonal weights 11 are secured on the lower end portions of the pins 8 beneath the rail 4 by set screws 12. As will be apparent the weights 11 constitute means for assuring the return of the pins 8 to lowered position by gravity. Also extending between the lay swords 2, in spaced relation beneath the lower rail 4, is a track 13 upon which a cam is mounted for reciprocation, said cam being designated generally by the reference numeral 14. The cam 14 comprises a block 15 which is mounted on a supporting arm 16, said supporting arm 16 being slideable on the track 13. Mounted on top of the block 15 is a face plate in the form of a channel member 17 through which the weights 11 ride when the cam 14 is actuated. It will thus be seen that the pins 8 are successively elevated and retained in elevated position for a brief length of time and then permitted to return to lowered position as the cam 14 is moved along the track 13.

The cam 14 is reciprocated on the track 13 through the medium of cables 18 which are windable on drums 19 on the lay swords 2. The cables 18 are connected, at one end, to an eye 20 which project from the supporting arm 16 of the cam 14. Any suitable means may be provided for alternately rotating the drums 19 in opposite directions for shifting the cam 14 back and forth on the lay in time with the operation of the loom. Mounted beneath the track 13 is a trough 21 for catching excess oil which may drip from said track 13. It may be well to here mention that oil from the reservoir 22 which is formed by the substantially tubular or hollow lower rail 4 flows by gravity down the pins 8 in a manner to lubricate the cam 14 and the track 13 as said cam

travels thereover. Attention is also invited to the fact that the polygonal weights 11 are slidably engaged with each other in side abutting relation in a manner to prevent lateral movement or wobbling of the pins 8, as illustrated to advantage in Figure 2 of the drawings.

The shuttle 5 includes a pair of spaced, opposed, substantially U-shaped frame members 23 between which upper and lower pairs of grooved wheels 24 and 25, respectively, are journaled. Mounted on one of the frame members 23 is a suitable support 26 for the bobbin 27. The weft 28 from the bobbin 27 is kept taut during the operation of the loom by a pair of co-acting, resilient jaws 29 which are mounted on a projection 30 on one of the frame members 23, said weft passing between the resilient jaws, as best seen in Figure 3 of the drawings. The grooved lower wheels 25 of the shuttle 5 are mounted for travel on the heads 10 of the pins 8.

The grooved upper wheels 24 of the shuttle 5 are operatively engaged with spaced lugs or corrugations 31 which depend from the upper rail 3. It will thus be seen that the construction and arrangement are such that the shuttle 5 is retained in a vertical position between the upper and lower rails 3 and 4. It will also be seen that the shuttle 5 is mounted to travel between the warps 32, said warps, in turn, passing between the corrugations 31 of the upper rail 3 and the projecting upper end portions of the guides 7 on the lower rail 4.

Briefly, the operation of the invention is as follows:—

As the cam 14 is moved back and forth on its track 13, the pins 8 are successively elevated in the manner suggested in Figure 2 of the drawings for engagement with one of the lower wheels 25 for driving the shuttle 5 in the direction in which said cam is traveling. As the cam 14 passes from beneath the pins 8, thereby permitting said pins to drop to lowered position, the returning pins engage the trailing wheel 25 and the shuttle 5 is in this manner retained at all times against idle movement between the rails 3 and 4. It will thus be seen that the shuttle 5 may be positively brought to a stop at any point in the shed simultaneously with the stopping of the cam 14.

It is believed that the many advantages of a shuttle motion for looms in accordance with the present invention will be readily understood, and although the preferred embodiment of the invention is as illustrated and described, it is to be understood that changes in the details of construction and in the combination and arrangement of parts may be resorted to which will fall within the scope of the invention as claimed.

What is claimed is:—

1. A shuttle motion for looms comprising spaced rails, a wheeled shuttle operable between the rails, pins mounted for vertical reciprocation on one of the rails and operatively engageable with certain of the wheels of the shuttle for actuating said

shuttle, heads on one end of the pins engageable with the shuttle wheels, weights on the other ends of the pins for returning the said pins to inoperative position by gravity, and means for successively elevating the pins, said means including a track mounted beneath one of the rails, a cam slidable on the track and operatively engageable with the weights, said cam including a substantially channel-shaped face plate engageable with the weights, and means for actuating the cam. 5

2. A shuttle motion for looms comprising spaced upper and lower rails, a wheeled shuttle operable between the rails, tubular guides mounted vertically in the lower rail, pins slidable in the guides and engageable with certain of the wheels of the shuttle for actuating said shuttle, means for successively elevating the pins, the guides projecting above the lower rail for the passage of the lower warps therebetween, and corrugations depending from the upper rail and 10 operatively engaged by the other wheels of the shuttle, said corrugations defining passages for the upper warps beneath the upper rail. 15

3. A shuttle motion for looms comprising spaced upper and lower rails, said lower rail 25 being hollow for the reception of a lubricant, tubular guides extending vertically through the lower rail and having ports therein for the passage of the lubricant thereinto, pins slidably mounted in the guides, heads on the upper ends 30 of the pins, a wheeled shuttle operable between the rails and engaged on the heads, weights on the lower ends of the pins for returning said pins to lowered position by gravity, and means for successively elevating the pins for actuating the 35 shuttle, the tubular guides extending above the lower rail for the passage of the lower warps therebetween.

4. A shuttle motion for looms comprising spaced upper and lower rails, said lower rail being hollow for the reception of a lubricant, tubular guides extending vertically through the lower rail and having ports therein for the passage of the lubricant thereinto, pins slidably mounted in the guides, heads on the upper ends of the pins, 40 a wheeled shuttle operable between the rails and engaged on the heads, weights on the lower ends of the pins for returning said pins to lowered position by gravity, and means for successively elevating the pins for actuating the shuttle, said 45 means including a track mounted beneath the lower rail, a cam slidably mounted on the track and operatively engageable with the weights, and means for actuating the cam, the guides projecting above the lower rail for engaging the heads 50 and supporting said heads in elevated position and for defining passages for the lower warps beneath the shuttle, the upper rail including depending corrugations defining passages beneath said upper rail for the upper warps. 55
